US0D1106785S

(12) **United States Design Patent** (10) **Patent No.:** **US D1,106,785 S**
(45) **Date of Patent:** **** Dec. 23, 2025**

(54) **PLIERS**

(71) Applicants: **ZHUJI ITOP HARDWARE TOOLS CO., LTD.**, Zhejiang (CN); **Zhejiang Iwiss Electric Co., Ltd.**, Zhejiang (CN)

(72) Inventors: **Xiaoming Deng**, Zhejiang (CN); **Jiulian Xu**, Zhejiang (CN)

(73) Assignees: **ZHUJI ITOP HARDWARE TOOLS CO., LTD.**, Zhuji (CN); **Zhejiang Iwiss Electric Co., Ltd.**, Leqing (CN)

(**) Term: **15 Years**

(21) Appl. No.: **29/924,859**

(22) Filed: **Jan. 22, 2024**

(51) LOC (15) Cl. **08-05**

(52) U.S. Cl.

USPC **D8/52**

(58) **Field of Classification Search**

USPC D8/51, 52, 54, 55, 56, 58

CPC B25B 27/10

See application file for complete search history.

(57) **CLAIM**

The ornamental design for pliers as shown and described.

DESCRIPTION

FIG. 1 is a top, front and right side perspective view of pliers showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the pliers which form no part of the claimed design.
